DOOR SPRING

Fred E. Snyder, Chicago, Ill., assignor to Gardner Wire Co., Chicago, Ill., a corporation of Illinois

Application July 6, 1936, Serial No. 89,040

6 Claims. (Cl. 16—72)

My invention relates to a screen door closer spring and the like and it has more particular reference to a device that may be quickly attached to a suitable support for use in connection with a screen door without the use of special tools. The device which I have invented consists of a coiled spring member or body that may be readily mounted upon a suitable bracket member, and it is provided with one or more lateral elements that project from such body to engage and exert pressure against the door to urge it to a closed position. I have provided means in connection with the lateral members for journaling suitable rollers which will permit of the easy operation of the device and will at the same time afford protection for the surface or finish of the door and door-frame that may be engaged by said device.

The primary object of my invention is to provide a device that is readily capable of operating in the manner herein set forth to accomplish the purposes for which it has been designed and to do this in an effective and dependable manner. Other objects are to provide a device of this character that is novel in construction; dependable in operation; easy to manipulate or install; simple and sturdy in the formation of its component parts so that it will not readily get out of order and will withstand hard usage; and is economical to manufacture so that it may be sold to the user for a reasonable retail price. Numerous other objects and advantages of my invention will be apparent to persons skilled in the art after the construction and operation of my device is understood from the following disclosure.

I prefer to accomplish the numerous objects of my invention and to practice the same in substantially the manner hereinafter fully described and as more particularly pointed out in the appended claims. The accompanying drawing is referred to for a better understanding of the construction, use, and operation of my improved door spring.

In the drawing:

Figure 1 shows my improved door spring in vertical elevation and applied to a screen door.

Figure 2 is a plan of the structure shown in Figure 1.

Figure 3 shows a slightly modified form in which my invention may be made and applied to a door, and

Figure 4 is a detail of the mounting bracket. The drawing, it will be understood, is more or less schematic in character, and is for the purpose of disclosing typical or preferred forms in which my device may be made. In this drawing like reference characters are used to identify like parts wherever such parts appear in the different views.

In the drawing, A designates the screen door; B the adjacent door frame or casing; and C the hinge of usual form, the leaves of which are secured respectively to the facing portions of the door and frame. D designates the body of a mounting bracket that is of thin metal and of substantially rectangular shape. There is an L-shaped extension on the body the lower shorter arm E of which projects horizontally from the lower portion of the body so as to position the longer arm F in a vertical position and spaced from the body as will be seen by reference to the detail shown in Figure 4. The longer vertical arm thus provides a post to receive the coiled body of the spring, and adjacent its upper end it is enlarged on one side to provide an abutment or shoulder the purpose of which will later appear. This bracket plate is inserted between the meeting surfaces of the door and casing and is anchored to one of such surfaces by screws or the like so that the L-shaped extension projects beyond the plane of the door and casing as seen in Figure 2.

The door spring which I have disclosed consists of a length of spring wire which has its intermediate portion wound into a coil 5, the convolutions of which preferably are in contact with each other as shown in the drawing and are in the form of a short cylindrical body. Any number of windings may be provided, depending of course upon the service required of the device. The ends of the windings or convolutions terminate in oppositely projecting arms 6 and 7 that are disposed substantially radially from the axis of the coil as will be seen by reference to Figure 2.

At its outer end the arm 6 is provided with a laterally extending portion which projects downward to provide a vertical journal 8 for a rotatable sleeve 9 of rubber or other suitable material which acts in the manner of a roller having its bearing on the journal 8. The wire at the lower end of this journal is bent laterally back toward the lower convolution of the coil to provide another arm 10 that is in the same vertical plane with respect to the upper arm 6. This arm 10 acts as a retainer for maintaining the roller 9 upon its journal. The bore 11 of the roller is slightly larger in diameter than the gauge of the wire forming the journal so that the roller will have free rotation.

The lower arm 7 is provided with a laterally extending portion 12 at its outer end that projects upwardly to provide a journal for another rotatable sleeve 13, also of rubber or other suitable material which acts as a roller in the same manner as roller 9 and which likewise has its bore of greater diameter than the gauge of the wire journal 12. At the upper end of the journal 12 the wire is bent laterally toward the upper 60

convolution of the coil 5 to provide an arm 14 corresponding with the arm 10 on the other side of the coil and which is in the same plane as the arm 7. This arm 14 acts as a retainer to maintain the roller 13 on its journal 12. The inner ends of arms 10 and 14 do not extend to the coil but terminate a short distance therefrom, as shown in Figure 1.

In normal position, and before being mounted upon the bracket the arms of the structure are disposed in planes that intersect each other at a somewhat acute angle as has been suggested by the dotted lines *x* in Figure 2. In order to mount the structure upon the bracket these arms are forced away from each other into planes beyond the planes of the arms when they are in the positions shown in Figure 2, and they are released after the coiled body 5 has been inserted over the post F of the bracket. In this position the arms are under tension with the rollers 9 and 13 bearing respectively against the surface of the door and door-frame. Thus, whenever the door is opened, the tension on the spring will be increased, and this tension is exerted against the door to close the same when the latter is released and retain the door closed. The lower convolution of the body 5 rests upon the top edge of bracket arm E and the upper convolution will be just below the shoulder or abutment *f* at the top of the post member and thereby retained against accidental dislodgement.

In the modified form shown in Figure 3, the coiled body 5 is formed with an end portion of a length of spring wire and its upper convolution extends radially outward to provide the arm 6. At the other end of the arm the wire is bent downwardly to provide the journal 8 on which the roller 9 is mounted, and is then bent in a reverse direction toward the coil to provide the retaining extension 10. The lower convolution of the spring body has a short downwardly bent stub 15 which normally engages a screw plate or mounting plate 16 that may be attached to the door-frame adjacent the edge of the door, which plate has an upstanding post 17 that is inserted into the coil body 5 and supports the structure. The stub 15 anchors one end of the spring coil body 5 and when the door is opened the arm 6 will cause a contraction of the spring so that the tension thereof assists in closing the door in substantially the same manner as in the preferred form of my invention shown in Figures 1 and 2.

It will be seen from the foregoing that the structure I have devised is very simple and is effective in performing its functions. It is made of few parts and continued opening and closing of the door does not cause a marring of the surface finish of the door and the door-frame because of the fact that the rollers 9 and 13 will rotate upon and not rub into these surfaces.

What I claim is:—

1. A screen door closer comprising a combination with a mounting device attached to a vertical support and embodying an upright member provided with an inwardly extending lug upon its upper portion, a coiled spring body adapted to fit about said member and consisting of a plurality of windings positioned below said lug, an arm projecting from one of said windings and urged towards the door, and a cylindrical roller rotatably mounted on a remote portion of said

arm and adapted for rolling movement upon the adjacent surface of the door.

2. A screen door closer comprising a coiled spring body, arms extending laterally in opposite directions from the end convolutions of said body, cylindrical rollers carried by the remote ends of said arms and adapted for rolling movement upon the surfaces of the door and its casing and means for mounting the body consisting of a plate interposed between the door and casing and a post projecting from said plate beyond the plane of the door and adapted to receive said coiled spring body, the upper end of the post having a lateral projection adapted to overhang the upper portion of said coiled spring body.

3. A screen door closer comprising a coiled spring body, arms extending laterally in opposite directions from the end convolutions of said body, transverse journals at the remote ends of said arms, retaining elements on said journals, cylindrical rollers rotatably mounted on said journals between said retaining elements and the adjacent ends of said arms, which said rollers are adapted for rolling movement upon the surfaces of the door and its casing and a bracket interposed between the door and its casing and embodying a post that projects outward from the door and its casing and adapted to receive said coiled spring body, said post provided with a projection at its upper end adapted to overhang said coiled spring body.

4. A screen door closer comprising a coiled spring body, arms extending in opposite directions therefrom for engagement respectively with the door and its casing, a bracket plate rigidly mounted between the edges of the door and its casing and embodying an outwardly disposed post upon which said coiled spring body is mounted, and a lateral lug on said post projecting towards said bracket plate and adapted to embrace the upper convolution of said coiled spring body.

5. A door closer comprising a coiled spring body, an arm extending from a convolution of the coil and disposed lateral to the axis of said body, a transverse member at the free end of said arm and providing a fixed journal disposed in parallel relation to the axis of said body, an extension projecting towards said body from the free end of said transverse member, and a cylindrical roller mounted for free rotation on said journal, whereby the adjacent portions of said arm and said extension provide retaining means for said roller, and said roller is adapted for rolling movement upon the adjacent surface of the door.

6. A door closer comprising a coiled spring body, arms extending from end convolutions of the coil and disposed in opposite directions lateral to the axis of said body, transverse members at the free ends of said arms and providing journals disposed in parallel relation to each other and to the axis of said body, extensions projecting towards said body from the free ends of said transverse members, and cylindrical rollers mounted for free rotation on said journals, whereby the adjacent portions of said arms and said extensions provide retaining means for the respective rollers, and said rollers are adapted for rolling movement respectively upon the adjacent surfaces of the door and door frame.

FRED E. SNYDER.
